US0D1113343S

(12) **United States Design Patent** (10) Patent No.: **US D1,113,343 S**
(45) Date of Patent: ** Feb. 17, 2026

(54) POD	3,441,168 A	4/1969	Luviano
(71) Applicant: The Cumulus Coffee Company , New York, NY (US)	3,799,381 A	3/1974	Acton
(72) Inventors: Gordon D. Row , Groton, MA (US); Demetrio D. Anaya , Somerville, MA (US); Adam Michael Paskow , New York, NY (US); Nathan J. Tyrowicz-Cohen , Arlington, MA (US); Zachary H. Zieper , Woburn, MA (US); Meshulem Gelman , New York, NY (US)	3,804,287 A	4/1974	Balocca et al.
(73) Assignee: The Cumulus Coffee Company , New York, NY (US)	3,856,187 A	12/1974	Chlystun
(**) Term: 15 Years	3,924,777 A	12/1975	Peyser
(21) Appl. No.: 29/903,165	4,397,402 A	8/1983	Keiji
(22) Filed: Sep. 20, 2023	4,648,528 A	3/1987	LaBarge et al.
(51) LOC (15) Cl. 07-06	4,664,292 A	5/1987	Jeans
(52) U.S. Cl. USPC D7/400; D9/518; D9/428	4,685,849 A	8/1987	LaBarge et al.
(58) Field of Classification Search USPC ..... D9/414, 416, 417, 419, 424, 428, 434, D9/435, 438, 440, 447, 454, 500, 501, D9/503, 516, 518, 519, 549, 763, 772, D9/779, 780, 902, 903, 906; D7/300, D7/302, 303, 305, 316, 317, 321, 397, D7/399, 400, 401, 602, 619.1, 667 CPC A23F 3/00; A23F 5/26; A47J 31/06; A47J 31/24; A47J 31/30; A47J 31/3623; A47J 31/3676; A47J 31/3695; A47J 31/368; A47J 31/40; A47J 31/407; A47J 31/41; A47J 31/44; B65B 29/02; B65B 29/022; B65B 29/025	5,052,573 A	10/1991	Zysset
See application file for complete search history.	D336,041 S	6/1993	Zama

CLAIM

The ornamental design for a pod, as shown and described.

DESCRIPTION

FIG. 1 is a front perspective view of a pod showing our new design;

FIG. 2 is a bottom perspective view thereof;

FIG. 3 is a right elevational view thereof;

FIG. 4 is a left elevational view thereof;

FIG. 5 is a front elevational view thereof;

FIG. 6 is a rear elevational view thereof.

FIG. 7 is a top elevational view thereof; and,

FIG. 8 is a bottom elevational view thereof.

In the drawings, the broken lines illustrate portions of the pod that form no part of the claimed design.
